UNITED STATES PATENT OFFICE

PATRICK H. ROBINSON, EMANUEL NIELSEN, AND EDWARD R. MROSS, OF RACINE, WISCONSIN, ASSIGNORS TO HAMILTON BEACH MANUFACTURING COMPANY, OF RACINE, WISCONSIN, A CORPORATION OF WISCONSIN

DRINK MIXER

Application filed October 15, 1926. Serial No. 141,698.

The invention relates to electric drink mixers, and more particularly to the automatic type in which manual placement of the receptacle into suitable retaining means and its removal therefrom are all the operative steps to be performed in a mixing operation.

The objects of the invention are: to provide an improved construction in which a 10 slide switch-operating member is engaged by the rim of the receptacle to start and stop the motor; to provide a simple and efficient manner of mounting the switch inside of the column, in which the switch parts are all assembled on a suitable strip prior to their insertion in the hollow supporting column to facilitate placement of the switch mechanism into the column; to utilize the securing devices for the elements of the receptacle-retaining-device to secure the switch-mount in 15 the column, thus dispensing with separate securing devices for the mount and the retaining device; to provide an improved switch mechanism in this type of mixer which insures the shifting of the switch to start the 20 motor responsively to placement of the receptacle.

Other objects will appear from the detailed description.

The invention consists in the several novel 30 features hereinafter set forth and more particularly defined by claims at the conclusion hereof.

In the drawings: Fig. 1 is a vertical section of a machine embodying the invention, 35 parts being shown in elevation. Fig. 2 is a perspective of the switching device separated from the column. Fig. 3 is a longitudinal section of the switching device, the contacts being shown in the position assumed when 40 the circuit is opened. Fig. 4 is a section on line 4—4 of Fig. 1. Fig. 5 is a section on line 5—5 of Fig. 1. Fig. 6 is a front elevation of the receptacle retaining hook.

The invention is exemplified in a mixer 45 comprising a hollow supporting standard A which has integrally formed therewith a base a adapted to rest on a counter or other suitable support; an electric motor B mounted on an integral elbow at the upper end of the 50 column; a shaft b depending from the motor-

shaft and directly driven thereby; an agitator b' fixed to the lower end of the shaft b; a receptacle E adapted to contain the constituents of the drink to be mixed; and an automatic retaining device for the receptacle 55 on the front of the column comprising a stud c to receive and serve as a support for the bottom of the receptacle E and a hook c' adapted to enter the open top of the receptacle E and hold it on the stud. There is sufficient clearance beneath and around the agitator and its shaft to permit the receptacle itself to be manually manipulated from below into the retaining device and its operative position around the agitator. This retaining device holds the receptacle in its 60 operative position when it has been thus shifted and permits direct removal of the receptacle by lowering it beneath the agitator. The front of the column A is concave as at 65 a' to guide the upper margin of the receptacle in its manual placement into the retaining device.

In this type of mixer, the motor is automatically started by placement of the receptacle into the retaining device and automatically stopped by its removal therefrom and it is desirable to provide a switch which is 70 positively shifted by the receptacle and which will be held in position to close the motor circuit while the receptacle is in its operative position. The switch-structure is enclosed in the hollow supporting-standard and assembled and connected to the electrical 75 conductors prior to its insertion in the standard, so that it will be readily and removably secured therein by the same screws or devices which secure the receptacle retaining hook and stud to the column.

The connections for supplying current to the motor comprise a conductor b leading directly from an ordinary switch plug (not shown) to the motor, and a conductor b' in which the switch is included to control the 80 operation of the motor. The entire switching mechanism is mounted upon and connected to a strip of metal D which has upper and lower forwardly offset ends or lugs d and d' so that the central portion thereof 85 will be spaced backwardly from the front 90 95 100

wall a^2 of the column A. The offset end or lug d has a screw-threaded opening to receive the screw c^2 which passes through hook c' so that the upper end of the strip may be securely supported in the column by said screw c^2 which passes through the front wall of the column and clamps both the hook and said strip to the column. The lower lug or offset end d' is also provided with a screw-threaded hole to receive the screw-threaded shank c^3 of the retaining stud c . Said shank is integral with the stud, passes through the front wall of column A and clamps the lower end of strip D and the stud to the column.

15 One branch of the conductor b' is connected, usually soldered, as at b^2 to a spring-contact-strip b^3 and the other branch of the conductor b' is similarly connected to a spring-contact-strip b^4 which is separated from contact b^3 to normally open the motor-circuit. Each of these contact-strips b^3 , b^4 is secured by a rivet b^5 to a strip of insulation b^6 . Rivets b^5 extend through the strip b^6 . A strip of insulation b^7 is interposed between strip b^6 and the back-face of the supporting-strip D to insulate the rivets b^5 from metal strip D. Additional rivets extend through supporting-strip D and insulating strips b^7 and b^6 to secure them all together. This provides a method of securing the contact-strips b^3 and b^4 to the supporting-strip D so the contacts will be effectively insulated from each other and from strip D. The circuit for the motor is adapted to be closed by a rivet or stud e which is adapted to bridge the gap between the terminals of the strips b^3 and b^4 . Stud e is riveted to a strip of insulation e' against which the resilient terminals of strips b^3 and b^4 are adapted to bear, the front face of stud e being preferably flush with the front face of said strip. A strip of insulation e^2 is interposed between the back of the stud-carrying strip e' and a slide F to which both of said strips are secured by rivets e^4 which pass through said strips and the slide. The strip e^2 insulates the stud e from the slide. The slide F is formed of a strip of metal which is bent to form a portion f' fitting against the front face of the supporting strip D, a lower portion f^2 also adapted to engage the strip D, and an intermediate offset portion f^4 extending across the back of the insulating strips e' and e^2 . Between the offset portion and the front portions, the strip is slotted, as at f^5 and f^6 so the strip D may be passed therethrough. The inclined strips f^8 at the sides of the slots f^5 and f^6 unite the relatively offset portions of the slide and straddle the supporting strip D so that the slide will be confined transversely on said strip. A tongue f^9 is struck backwardly from the portion f' of strip F to form a hook to which is connected one end of a retracting spring g for the slide F. The other end of the spring is

connected to a screw g' which extends through the supporting strip D and is provided with a head g^2 at the front of said supporting strip. The side has a slot g^3 , the upper ends of which serve as a stop for the slide and the slot permits the slide to move a limited distance relatively to the supporting strip. The resiliency of the contact strips b^3 , b^4 which engage the insulating strips e' on the slide presses the slide rearwardly so that the portions f' and f^2 of the slide will be frictionally held against the front face of the supporting strip D. This also insures contacting engagement between the strips b^3 and b^4 and the bridging stud e . A strip of paper h in back of the switch structure has one of its ends secured by the rivet d^4 to strip D and the branches of the conductor b' extend through perforations in the strip. The upper end of slide F is bent forwardly, as at f^{10} and extends through a hole a^5 in the front wall of supporting-column A in back of the receptacle-retaining hook c' . The forwardly projecting portion f^{10} of the slide extends into the path of the rim of the receptacle E and forms an abutment, which, when the rim is slipped upwardly along the standard, will operate the slide upwardly a sufficient distance to shift stud e which is movable therewith into position to bridge the gap between contact strips b^3 and b^4 and thus close the circuit to start the motor. When the receptacle is removed the spring g will retract the slide and shift the stud e so that it will open the circuit between the contacts b^3 and b^4 .

In manufacturing the mixers, the entire switching unit with the conductor-connections made is assembled on the supporting strip D before it is inserted from below into the column A. The lower end of said column is open for that purpose. The assembled structure with the branches of conductors b' secured to the contacts b^3 , b^4 are lifted in the column so the threaded holes in lugs d and d' of the strip D register with the screws c^2 and c^3 of the retaining hook and retaining stud respectively. The entire structure will be properly mounted and secured therein by turning the inner ends of said screws into the strip D and clamping it to the back face of the front wall of the column. If at any time, the switch should become defective or is to be replaced, the entire switching unit may be readily removed by loosening the screws c^2 and c^3 . Thus this construction makes it possible to quickly repair any defect therein, and also to quickly replace the unit, if desired. The hook c' is of sufficient width to conceal the opening a^5 and cover it so that none of the contents of the receptacle will be splashed into the column through said opening.

The invention exemplifies an electric drink mixer of the type in which placement and the

removal of the receptacle are all that are necessary in a mixing operation, in which the switching structure may be assembled and inserted into the supporting column, and secured therein by the retaining device or screws of the receptacle holder; in which a slide is engaged by the upper rim of the receptacle in transit to its position to be held by a stationary retaining hook so that the switch will be positively operated; and in which the switching mechanism is simple in construction and efficient in operation and may be produced at a low cost.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine of the character described, the combination of a hollow supporting column, an electric motor mounted at the upper end of the column, a shaft provided with an agitator and driven by the motor, means to retain a receptacle in operative position beneath the motor upon manual manipulation of the receptacle itself into such position, comprising stationary elements to engage the upper and lower portions of the receptacle, a switch connected to control the operation of the motor, and a switch-operating slide in the column, said slide being engageable and movable upwardly by the rim of the receptacle, in manipulation of the latter into operative position, to close automatically the switch.

2. In a machine of the character described, the combination of a hollow supporting column, an electric motor mounted at the upper end of the column, a shaft provided with an agitator and driven by the motor, means to retain a receptacle in operative position beneath the motor upon manual manipulation of the receptacle itself to such position, comprising a bottom support, a switch connected to control the operation of the motor, a switch-operating slide in the column, said slide being engageable and movable upwardly by the rim of the receptacle, in manipulation of the latter into operative position, to close automatically the switch, and a spring applied to move the slide downwardly and hold it against the receptacle.

3. In a machine of the character described, the combination of a hollow supporting column, an electric motor mounted at the upper end of the column, a shaft provided with an agitator and driven by the motor, means to retain a receptacle in operative position beneath the motor upon manual manipulation of the receptacle itself into such position, comprising elements to engage the upper and lower portions of the receptacle, a switch con-

nected to control the operation of the motor, mounted in the column, and a vertically movable switch-operating slide in the column and engageable by the upper rim of the receptacle, in manipulation of the latter into operative position, to close automatically the switch.

4. In a machine of the character described, the combination of a hollow supporting column, an electric motor mounted at the upper end of the column, a shaft provided with an agitator and driven by the motor, means to retain the receptacle in operative position beneath the motor upon manual manipulation of the receptacle itself into such position, comprising a bottom support, a switch connected to control the operation of the motor, mounted in the column, a vertically movable switch-operating member engageable and movable upwardly by the upper rim of the receptacle, in manipulation of the latter into operative position, to close automatically the switch, and spring means to press the slide against said rim and the receptacle against the bottom support.

5. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, comprising an element adjacent the column, a switch connected to control the operation of the motor in the column, a movable switch-operating member in the column and engageable by the rim of the receptacle, a supporting strip in the column for the switch and said member, and means for conjointly securing said element and said strip to the column.

6. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, comprising a plurality of elements on the column to engage the upper and lower portions of the receptacle, a switch connected to control the operation of the motor, in the column, a switch-shifting member in the column and engageable by the rim of the receptacle, a supporting strip in the column for the switch and said member, and devices for conjointly securing the elements and said strip to the column.

7. In a machine of the character described, the combination of a hollow supporting column, an electric motor mounted at the upper end of the column, a shaft provided with an agitator and driven by the motor, means for retaining the receptacle in operative posi-

- tion beneath the motor upon manual manipulation of the receptacle itself into such position, comprising an element adjacent the front of the column, a switch connected to 5 control the operation of the motor, in the column, a vertically movable slide in the column engageable by the rim of the receptacle, a supporting-strip for the switch and the slide, and means for conjointly securing said element and said strip to the column.
- 10 8. In a machine of the character described, the combination of a hollow supporting column, an electric motor mounted at the upper end of the column, a shaft provided with an 15 agitator and driven by the motor, means for retaining the receptacle in operative position beneath the motor upon manual manipulation of the receptacle itself into such position, comprising a hook and a stud on the 20 front adjacent the column to engage the upper and lower portions of the receptacle respectively, a switch for controlling the operation of the motor, in the column, a supporting strip in the column, for the switch, and screws for conjointly securing the strip 25 and the hook and stud to the column.
9. In a machine of the character described, the combination of a hollow supporting column, an electric motor mounted at the upper 30 end of the column, a shaft provided with an agitator and driven by the motor, means for retaining the receptacle in operative position beneath the motor upon manual manipulation of the receptacle itself into such position, comprising a hook and a stud adjacent the front of the column to engage the upper 35 and lower portions of the receptacle respectively, a switch for controlling the operation of the motor, in the column, a supporting strip in the column, for the switch, a switch-operating member operable by the receptacle and mounted on said strip, and screws for conjointly securing the strip and the hook and stud to the column.
- 40 10. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, comprising a bottom support, a switch for controlling the operation 45 of the motor, in the column, a switch-operating member in the column and engageable by the rim of the receptacle, and a supporting strip by which the switch and member are carried, the strip, switch and member being unitarily insertable into and removable from the column.
- 50 11. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, comprising stationary elements 55 to engage the upper and lower portions of the receptacle, a switch for controlling the operation of the motor, in the column, a switch-operating member in the column and engageable by the rim of the receptacle, and a supporting strip by which the switch and member are carried, the strip, switch and member being unitarily insertable into and removable from the column.
- 60 12. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, a switch for controlling the operation of the motor, in the column, a vertically movable switch-operating slide engageable by the rim of the receptacle, and a supporting strip by which the switch and member are carried, the strip, switch and slide being unitarily insertable into and removable from the column.
- 65 13. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, a switch for controlling the operation of the motor, in the column, a switch-operating member engageable by the rim of the receptacle, a spring for retracting said member, and a supporting strip by which the switch, member and spring are carried, the strip, switch, member and spring being unitarily insertable into and movable from the column.
- 70 14. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, a switch for controlling the operation of the motor comprising contacts, a supporting strip in the column on which one of the switch-contacts is mounted, and a slide, guided by said supporting strip, carrying another contact, having portions extending to the opposite sides of the strip, and provided with means engageable by the receptacle to shift the last mentioned contact to 75 open and close the switch.
- 75 80 85 90 95 100 105 110 115 120 125 130

15. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, a switch connected to control the operation of the motor, comprising a pair of contact strips and a bridging contact, a supporting strip, in the column, to which the contact strips are secured, and a slide carrying the bridging contact, guided by said supporting strip mounted on the strip, and provided with means engageable by the receptacle to shift the bridging contact to open and close the switch.

16. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, a switch for controlling the operation of the motor comprising a pair of contact strips and a bridging contact, a supporting-strip, in the column, to which the contact strips are secured, and a slide carrying the bridging contact and having an opening therein through which the strip extends to guide the slide, and provided with means engageable by the receptacle to shift the bridging contact to open and close the switch.

17. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, a switch for controlling the operation of the motor, in the column and comprising a pair of resilient contact strips and a bridge-contact, a supporting strip in the column, to which the contact strips are secured, and a slide guided by said supporting strip, carrying the bridging-contact, and provided with a part extending through the front of the column and engageable by the receptacle to shift the bridge-contact to open and close the switch.

18. In a machine of the character described, the combination of a hollow supporting column, an electric motor mounted at the upper end of the column, a shaft provided with an agitator and driven by the motor, means for retaining the receptacle in operative position beneath the motor upon manual manipulation of the receptacle itself into such position, a switch for controlling the operation of the motor, in the column and comprising a pair

of resilient contact strips and a bridge-contact, a supporting strip on which the contact strips are mounted, extending vertically in the column and having forwardly offset ends, and a slide mounted on the strip, carrying the bridge-contact, and provided with a part engageable by the receptacle to shift the bridge-contact to open and close the switch.

Signed at Racine, Wisconsin, this 7th day of October, 1926.
